V. COLLIER

SEATING SURFACE

Filed Dec. 14, 1922

Inventor -
Vincent Collier,
By - A. Smiga, att.

UNITED STATES PATENT OFFICE.

VINCENT COLLIER, OF WORCESTER PARK, ENGLAND.

SEATING SURFACE.

Application filed December 14, 1922. Serial No. 606,954.

To all whom it may concern:

Be it known that I, VINCENT COLLIER, a British subject, residing at Elmcroft Nursery, London Road, Worcester Park, in the 5 county of Surrey, England, have invented certain new and useful Improvements in and Relating to Seating Surfaces, of which the following is a specification.

This invention relates to a new method 10 for attaching canvas or other fabric or the like to rails or the like of wood or metal or other suitable material, the object being to provide a detachable seating surface capable of being attached to any rails of suitable 15 section, whether forming part of a deck or hammock chair or similar article of furniture, or merely supported by pillars, posts or other suitable means. The object in the latter case is for the fixed rails, placed in the 20 requisite positions, for example round sports grounds and other places, to be temporarily converted into rows of deck or hammock chairs or similar articles of furniture by fitting thereto a number of independent seating 25 surfaces.

According to the invention, each end of a length of canvas or other fabric to constitute a seat is stiffened and modelled substantially in the plane of the length of 30 fabric, for instance by tightly sheathing therein in the plane of the fabric, a strip of millboard or other suitable material which preferably is slightly resilient and more or less pliable. Hard wood, enveloped 35 in paper, wash leather or other resilient material could also be used. The said stiffening material should preferably be flat on one side and slightly rounded or beveled on the other; it must not exceed in width the 40 width of a flat or substantially flat face or surface which it is essential for the rails to have and its thickness should preferably be about one eighth of its own width.

By this construction and arrangement 45 when the flat side of one of the stiffened and modelled ends of the seating surface is placed against a flat surface of the rail, for instance against one side of a quadrangular rail (with or without blunted or bevelled 50 edges) and the fabric is tightly wound round same, and when pulled upon, the fabric automatically becomes fixed with respect to the rail as the tensional strain upon the edge of the said stiffening material or

shape is neutralized by the greater strain 55 upon the surface thereof caused by the convolutions of the fabric.

For convenience of manufacture the said stiffening material or shape is preferably inserted in the fabric in the following manner:—Each end of the length of fabric constituting the seating material is folded over and stitched down so as to form a narrow sheath barely large enough to contain the said stiffening material or shape, so that 60 when same is inserted therein the fabric constituting the said sheath is fully distended and no creases or pleats are formed. A sheath is preferable to a sleeve, as one end is closed and the other left open so that the 65 said stiffening material or shape may be extracted when the seating surface is sent to the wash.

When fitted with these insertions which it 70 will be seen do not come in contact with the frame or other supports but are merely used to stiffen and model the ends of the fabric the seating surface is complete and is attached to bottom and top rails in the following manner:—

The flat side of one of the stiffened and modelled ends thereof is placed immediately 75 against the under side of the lower or bottom rail, round which the fabric is then wound, the other end of the fabric is now passed 80 over and round the top or higher rail behind 85 which the other stiffened and modelled end is slipped, so as to come between the rail and the convolutions of the fabric. The weight of the occupant of the chair alone 90 suffices to fix and keep the seating surface in position. The greater the weight the tighter the grip.

And in order that the invention may be 95 better understood, it will now be described with reference to the accompanying drawings, in which:—

Fig. 1 shows a perspective view of a portion of the proposed stiffening material or shape.

Fig. 2 shows a similar view with the stiffening material or shape inserted in the fabric.

Fig. 3 shows perspective diagram of a portion of a seating surface with its stiffened ends attached to bottom and upper rails.

Figs. 4, 5 and 6 show somewhat diagram-

matic fragmentary perspective views illustrating examples of modified cross sections of rails and stiffeners.

Fig. 7 shows sectional diagram illustrating my invention fitted to an ordinary deck chair.

Fig. 8 shows diagrammatic sketch of a sports pavilion or the like fitted with the invention.

10 The comparative thickness of the fabric or the like in Figs. 2 to 6 is exaggerated for a clear showing of the invention.

Referring to Figs. 1-3, 10 are stiffeners or shapes which have one flat side 11, the other side having bevelled or rounded edges 12. 13 is the fabric or the like constituting the seating surface. This is formed with sheaths 14, at the ends, into which the stiffeners 10 are inserted.

20 A bottom rail 15 is shown in Fig. 3 and a top rail 16. Both the rails are quadrangular in cross section with bevelled or rounded corners; they may be supported in any suitable manner.

25 In use the flat side 11 of one of the stiffeners is placed on the under surface of the bottom rail 15 and the fabric 13 wrapped or coiled around the rail and stiffener as shown. The other end of the fabric is now placed over the top of and around the upper rail 16, and the other stiffener positioned as shown with its flat face 11 against one of the flat faces of the rail 16.

30 Upon pulling on the fabric 13 in the direction of the arrows 17 and 18 (which would be the direction of pull due to the weight of a person sitting on the fabric 13) it will be appreciated that the tension in the fabric pulling on the stiffened edges is neutralized as it causes the surfaces thereof to bear tightly against the convolutions of the fabric, this grip increasing with the tensional pull or weight.

35 In Fig. 4, a rail is shown having a flat face for the stiffener to engage, the other

portion of the surface being generally rounded.

A triangular rail with rounded corners is shown in Fig. 5.

Both the rail and the stiffener in Fig. 6 are shaped as segments of a circle.

The upper and lower rails of an ordinary deck chair are generally quadrangular, such a device is indicated in Fig. 7, with a seating surface of fabric 13, attached to the rails, according to the invention.

The sports pavilion shown in Fig. 8 has top rails 16, supported by triangular brackets 19, attached to the outer walls 20 and bottom rails 15, attached by suitable brackets to the flooring. Between each pair of rails 15 and 16, a desired number of seating surfaces constituted by fabric or the like 13 is disposed as shown.

It is obvious that the ends of the seating surfaces may be stiffened, substantially in the plane thereof, by other means than those shown and further that rails of any other suitable cross section can be employed.

What I claim as my invention and desire to secure by Letters Patent of the United States of America is:—

In an article of furniture such as a chair a supporting bar having a flat exterior side, and a seat of fabric arranged with one end wrapped entirely around all sides of said bar in a lapping coil and provided at the end with a stiffening bar bearing against said flat side of the supporting bar and between the same and that portion of said coil which is opposite said flat exterior side of the bar so that weight imposed on said seat fabric tightens the same around said supporting bar, the said stiffening bar preventing casual detachment of said fabric from said supporting bar.

In testimony whereof, I have hereunto subscribed my name.

VINCENT COLLIER.
